Des. 1101

J. W. Lane, of Newton, N. J.
Letters Patent No. 1101, dated May, 1859

The schedule referred to in these Letters Patent and making part of the same,

To all whom it may concern:

Be it known that J. W. Lane, of Newton, in the County of
Sussex, and State of New Jersey, have invented or produced, a new and original design for
the circular cast iron plates of air tight Stoves, and I do hereby declare that the follow-
ing is a full, clear and exact description of the same, reference being had to the accompa-
nying drawings and to the letters of reference marked thereon.

Figure 1. is a top view of the plate showing the peculiar configuration of its
rim.

Figure 2. is a diametrical section taken through the red lines of figure 1.

The character of the design consists in Casting in Alto-relievo,
around and upon the upper face of the inclined edge of the plate, a Star and Crescent
arranged so that each point of the Crescent touches another so as to form a chain of Cres-
cent all joined at their points and encircling the plate, between each crescent is a
Star and the two when combined form a neat and handsome border.

A. represents the plate, plain upon its horizontal face with
a rim slightly inclined; upon this rim are arranged Crescents B. and Stars C. each
point of the Crescents touching that of the other, the Stars C. being arranged between each
crescent as shown in the drawings by figure 1.

What I claim as new and desire to secure by Letters Patent, is,
The Star and Crescent in alto-relievo forming a border for circular plates for stoves when arranged
as above described and represented.
